DESIGN FOR A COLOR COMPARATOR

Morris Resnick, Passaic, N. J.

Application February 27, 1947, Serial No. 137,215

Term of patent 14 years

(Cl. D57—1)

To all whom it may concern:

Be it known I, Morris Resnick, a citizen of the United States of America, residing at Passaic, in the county of Passaic and State of New Jersey, have invented a new, original, and ornamental Design for a Color Comparator, of which the following is a specification, reference being had to the accompanying drawing, forming a part thereof, wherein:

Fig. 1 is a perspective view of a color comparator, from the front, showing my new design;

Fig. 2 is a perspective view thereof from the rear; and

Fig. 3 is a plan view thereof with part of the viewing tube broken away.

I claim:

The ornamental design for a color comparator, substantially as shown.

MORRIS RESNICK.
